UNITED STATES PATENT OFFICE.

JAMES S. COPELAND, OF HARTFORD, CONNECTICUT, ASSIGNOR TO THE POPE MANUFACTURING COMPANY, OF SAME PLACE AND PORTLAND, MAINE.

DESIGN FOR A BICYCLE-FRAME.

SPECIFICATION forming part of Design No. 28,587, dated May 10, 1898.

Application filed March 21, 1898. Serial No. 674,686. Term of patent 14 years.

To all whom it may concern:

Be it known that I, JAMES S. COPELAND, a citizen of the United States, and a resident of Hartford, in the county of Hartford and State of Connecticut, have invented a new and original Design for a Frame for Bicycles; and I do hereby declare the following, when taken in connection with the accompanying drawings, and the letters of reference marked thereon, to be a full, clear, and exact description of the same, and said drawings constitute part of this specification, and represent, in—

Figure 1, a view in side elevation of the frame, and in Fig. 2 a detail top view of a portion of the lower rear fork.

My invention relates to a design for a bicycle-frame; and it consists in the configuration of the structure, as hereinafter described, and shown in the accompanying drawings.

The frame is of the "diamond" type in general outline, with the socket-head *a*, upper center tube *b*, lower center tube *c*, upper rear fork *d*, and rear fork *e*. The crank-bracket *f* is cylindrical in outline with enlarged end *g*, having a tapered projection *g'*, merging into the lower rear fork *e*.

At the junction of the upper and lower rear forks appears a bulbous part *h*, located within an inclosing frame. Behind the rear part *i* of the frame, when seen in side view, appears a circular figure *k*. This figure when viewed from the top appears in the shape of an oblong part with rounded edges *l m*. The front portion *n* of the inclosing frame terminates in a cylinder connecting the frame and the bulb *h*.

The essential feature of my design consists in the bulbous enlargement located within an inclosing frame uniting two of the frame parts.

I claim—

The design for a frame for a bicycle substantially as shown and described.

In witness whereof I have signed this application in the presence of two subscribing witnesses.

JAMES S. COPELAND.
